(57) **CLAIM**

The ornamental design for a drawing board set, as shown and described.

DESCRIPTION

FIG. 1 is a perspective view of a drawing board set showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the drawing board set where the drawing board set is in a first configuration of use;

FIG. 10 is a perspective view of the drawing board set where the drawing board set is in a second configuration of use;

FIG. 11 is a perspective view of the drawing board set where the drawings board set is in a storage state; and,

FIG. 12 is an enlarged view of portion 12 shown in FIG. 1. The dash-dash broken lines in FIGS. 1-6 illustrates portions of the drawing board set that form no part of the claimed design. The dash-dash broken lines in FIGS. 9 and 11 illustrating drawing boards depict environment that form no part of the claimed design. The dot-dash broken lines represent boundaries of the enlarged portion and form no part of the claimed design.

1 Claim, 12 Drawing Sheets
